CLEANING DEVICE

Theodor Sendler, Stettin, Germany

Application August 4, 1934, Serial No. 738,387
In Germany August 24, 1933

3 Claims. (Cl. 15—119)

This invention relates to cleaning devices for floors, windows, walls and the like embodying a carrier for a moisture absorbing cleansing element of sponge like material, such as a pad of 5 sponge rubber, the carrier having a manipulating handle connected thereto, and a handle carrying a presser plate detachably connected to the carrier for the moisture absorbing cleansing element and operative to position the presser plate into engagement with the moisture absorbing cleansing element in opposed relation to its carrier and by pressure applied to the handles squeeze the cleansing element between its carrier and the presser plate to expel moisture from the cleansing 10 element.

In cleaning devices of this character heretofore the manipulating handle has been secured in fixed angular relation to the carrier for the cleansing element. In the use of the cleaning 15 device with the manipulating handle so connected to the carrier for the cleansing element it is impossible to move the cleaning device below articles of furniture which are in close proximity to the floor with the result that the furniture 20 may be easily damaged by the manipulating handle striking against the same. In other instances the presser plate carrying handle has been permanently pivotally mounted at the upper or lower side of the manipulating handle to have oscillatory movement to position the presser plate into engagement with and squeeze the cleansing element between its carrier and the presser plate to expel moisture from the cleansing element, with the result that the cleaning device is not 25 only cumbersome in use, but the presser plate carrying means will serve as an obstruction to a greater extent than when the manipulating handle is fixed in angular relation to the carrier for the cleansing element to prevent passing the 30 cleaning device beneath articles of furniture in the use of the cleaning device.

It is the object of the invention to provide an improved construction and arrangement of cleaning device of this character to overcome the 45 disadvantages above set forth, and to provide a cleaning device that is simple in structure and highly efficient in use.

In carrying out the invention a manipulating handle is pivotally connected to a carrier for a 50 moisture absorbing cleansing element so as to be capable of being adjusted to different angular positions relative to the carrier for the cleansing element, and a presser plate carrying handle adapted to be detachably and pivotally connected to the carrier for the cleansing element where-

by when said handle is connected to the carrier for the cleansing element it may be readily adjusted to position the presser plate into engagement with the cleansing element in opposed relation to the carrier for the cleansing element and 5 said handle to extend adjacent and approximately parallel to the manipulating handle, whereby forces may be readily applied to the handles to exert pressure on the carrier for the cleansing element and the presser plate to squeeze the 10 cleansing element therebetween and expel moisture from the cleansing element, and when the moisture has been expelled from the cleansing element the presser plate carrying handle may be readily detached from the carrier for the 15 cleansing element and the cleaning device manipulated to pass the cleaning device beneath articles of furniture and the like without either the manipulating handle or the moisture expelling means constituting an obstruction to such manipulation and tending to damage the furniture. 20 By the provision of the adjustable manipulating handle and the detachable squeezing means it is possible to clean walls, windows and other vertical or upright surfaces with the entire available surface of the cleansing element, since the manipulating handle may be adjusted relative to the cleansing element so that it may assume a position in close proximity to the wall, window or other surface being cleaned and clean the surface by substantially a vertical reciprocatory motion of the cleaning device.

The results capable of being obtained by a cleaning device according to the present invention are not possible with devices wherein the 35 manipulating handle is secured in fixed angular relation to the carrier for the cleansing element, or when the pressing or squeezing means is permanently connected to the cleaning device.

An embodiment of the invention is illustrated 40 in the accompanying drawing, in which

Figure 1 is an elevational view of a cleaning device embodying the invention and showing the same in a position of use.

Figure 2 is an elevational view of the presser 45 plate carrying handle, and

Figure 3 is a plan view of the cleaning device and presser plate carrying handle connected thereto, and showing the manner of detachably connecting the presser plate carrying handle to 50 the cleaning device and in position prior to adjusting the same to position the presser plate into engagement with the cleansing element in opposed relation to the carrier therefor.

In the embodiment of the invention illustrated 55

- in the drawing there is provided a manipulating handle *a* secured at one end in a sleeve portion at one end of a member *b* to carry the handle, said member being provided with a bifurcation *b'* at the opposite end whereby it is pivotally connected to a plate *d* by a pin *c*, the plate *d* being secured in edgewise relation to the back of a body or carrier for a moisture absorbing cleansing element, said carrier being shown in the form of a plate *e* with the plate *d* extending transversely of the plate *e* midway its ends. On the front or face of the plate *e* opposite the plate *d* there is attached by suitable means a facing of moisture absorbing cleansing material, shown in the form of a pad *f*, such as sponge rubber. The carrier or body *e* may be provided with openings or apertures to reduce the weight thereof, as indicated at *e'* in Figure 3. In the preferred form of the means to attach the pad *f* to the plate *e* there is provided on one face of the pad two pockets *f'*, one adjacent each end of the pad, formed of flat pressed tubing of elastic material, such as rubber. The pockets may be open at both ends, or if desired only at the ends opposed to each other, to permit of engagement therein of the plate *e*. To mount the facing or pad *f* on the plate *e* one end of the plate *e* is engaged in one pocket *f'* and then the other pocket is stretched sufficiently to engage it over the opposite end of the plate *e*. Due to the elasticity of the material of the pockets and of the facing or the pad *f* this operation may be readily performed. The facing or pad *f* may consist of separate sections, each section being equal in size to one-half of the plate *e*, and in which case each section of the pad is provided with a pocket *f'*. The plate *d* is provided with two recesses *g*, *h* in the edge thereof, the recess *h* extending approximately parallel to the back of the plate *e* and the recess *g* spaced therefrom and disposed at an angle of approximately 45 degrees to the back of the plate *e*. The sleeve *b* slidably carries a spring influenced detent in the form of a bolt *i*, which projects downwardly to such an extent under the action of the spring that the lower end thereof, dependent on the position of the handle *a*, engages in one of the recesses *g*, *h* and thus holds the handle *a* in predetermined angular position relative to the plate *e*, and when the bolt engages in the recess *h* the handle will extend substantially parallel to the back of the cleaning device. The end of the plate *d* opposite the end arranged with the recesses *g*, *h* is constructed to form a hook opening rearwardly of the front edge of the plate *b* and forward side of the body *e*. To expel moisture from the facing or pad *f* there is provided a presser plate *o*, which may consist of sheet metal having a plurality of openings or apertures and slots therein (Figure 3) to reduce the weight of the plate and permit of the passage of liquid squeezed from the cleansing element or pad *f*. The presser plate *o* is pivotally supported intermediate its ends and arranged at one side, the lower side as viewed in Figures 2 and 3, of a flattened end portion of a member *z* the opposite end portion of which member is arranged as a sleeve for the engagement therein and carrying of a handle *m*. To pivotally support the plate *o* it is provided with a pair of perforated spaced ears *l* midway its ends and arranged centrally of the side edges of the plate and between which ears the flattened end portion of the member *z* is engaged and pivotally connected thereto by a pin *z'* engaged in the ear

perforations and a perforation in the flattened portion registering with the ear perforations, whereby the presser plate *o* is adapted to have movement on the longitudinal center of the plate and transversely of the handle *m*. The plate *o* is urged in a direction to engage the front marginal portion with the flattened portion of the member *z* forwardly of the pivotal connection of the plate *o* by a spring *x* coiled about the pivot pin *z'* with one end of the spring engaging the plate *o* and the opposite end engaging the member *z* rearwardly of the pivot support of the plate *o*. By the connection of the presser plate *o* with the handle member *m* the presser plate is adapted to be carried and manipulated by the handle, and if desired the sleeve portion of the member *z* may be provided with a hook *v* that may be readily engaged upon a suitable support to support the device therefrom.

A bell-crank member constituting two like angle plates *j* one angle portion of which is of greater length than the other angle portion are secured together in spaced relation by a spacing member *n*, the plates *j* being spaced apart a distance somewhat greater than the thickness of the plate *d*. The bell crank member is connected at the end of the angle portion of greatest length to the free end of the flattened portion of the member *z* by a pin *k*, and the plates are connected together at the ends of the other angle portion by a pin *p*.

In use the manipulating handle *a* is locked in position to extend in angular or parallel relation to the plate *e* by the bolt engaging one of the recesses *g*, *h*, and when the bolt is engaged in the recess *g*, as shown in Figure 1, is locked to extend in angular relation to the plate *e*. After the manipulating handle *a* has been locked in either one of said positions the cleaning device is ready for use to clean floors, windows, walls and the like. The body *e* with the pad of absorbent material of the cleaner is immersed in water or other cleaning fluid, the material of the pad absorbing the water, which may then be applied by the pad to the surface to be cleaned. Upon the cleansing of the surface the pad naturally becomes dirty and soiled, and as this also applies to the water used, it is necessary that the water be frequently expelled from the pad, and also that the water be sufficiently expelled from the pad so that the water applied to the surface to be cleaned will be absorbed by the material of the pad from the cleaned surface.

To expel moisture, such as water, from the cleansing pad and thus cleaning the pad, the expelling means is pivotally connected to the body *e* of the cleaning device by engaging the hook *y* of the plate *d* between the plates *j* of the bell crank member so that the pin *p* will straddle the hook *y*, as indicated in dot and dash lines in Figure 1, with the bell crank member extending transversely of the front edge of the body *e* and positioning the presser plate carrying handle *m* as indicated at A in dot and dash lines in Figure 1. After the presser means has been so connected to the body *e* of the cleaning device the handle *m* is moved to position to extend substantially in the plane of and diverging from the manipulating handle *a* and with the presser plate *o* engaging the pad in opposed relation to the plate *e*, as shown in dot and dash lines B in Figure 1. To squeeze the pad between its carrier *e* and the presser plate *o* to expel water therefrom pressure is applied to the manipulating handle *a* and the presser plate carrying handle *m* causing

said handle *m* to move to the position indicated by dot and dash lines *C* to extend adjacent and approximately parallel to the manipulating handle *a* the force on the handles exerting a strong pressure on the pressure plate *o* and the pad carrier *e* and thereby compressing the pad *f* and the expelling of the water therefrom, it being possible to compress the pad sufficiently to expel practically all of the water from the pad.

10 By repeated immersion of the cleaning device in clean water and repeated compression of the pad *f* foreign substances will be freed and expelled from the pad. The pad may be compressed to such an extent that practically all of the water 15 will be expelled therefrom and leave the pad substantially dry, so that after removal of the presser means from the cleaning device the surface under treatment may be polished in a dry state by the cleaning device.

20 Having described my invention, I claim:

1. In a cleaning device, a plate adapted to carry an absorbent material on the face thereof and arranged with a hook portion midway its ends and at one side of the longitudinal center 25 of the back of the plate, a handle pivoted on said plate to have transverse movement on an axis extending longitudinally of the plate, a second handle, a presser plate pivotally mounted intermediate its ends along its longitudinal center at 30 the side of said second handle to have movement on an axis extending longitudinally of the presser plate and transversely of said second handle, a spring to urge the presser plate into engagement with the second handle forwardly of the pivotal 35 mounting of the presser plate, and means pivotally connected to the end of said second handle adapted to be removably and pivotally engaged with the hook portion of the first plate to connect said second handle to the first plate and 40 permit operation of said second handle to position the presser plate in opposed relation to and into engagement with the absorbent material on the face of the first plate and said second handle to extend adjacent and approximately 45 parallel to the first handle and in said position of the handles move the presser plate in a direction toward the first plate and exert a squeezing force on the absorbent material on the face of the first plate to expel moisture from the absorb- 50 ent material.

2. In a cleaning device, a plate carrying a pad of absorbent material on one of its faces, a second plate fixed to the opposite face of said first plate to extend edgewise transversely of and 55 midway the ends of the first plate, and said second plate arranged with a rearwardly opening hook portion at one end thereof and at a

side of the first plate, a handle carrying member pivoted on the second plate to have transverse movement on an axis extending longitudinally of the first plate, a second handle carrying member, a presser plate conforming in shape to the first plate pivotally mounted intermediate its ends on said second handle carrying member to be disposed at the side thereof and have movement on an axis extending longitudinally of the presser plate and transversely of said second handle carrying member, a pair of like bell crank plates connected in spaced relation pivotally connect at one end to the second handle carrying member and having a pin fixed in and extending between the opposite ends of the plates adapted to straddle and engage the hook portion of the second plate to connect the second handle carrying member to the first plate and permit operation of said second handle carrying member to extend adjacent and approximately parallel to the first handle carrying member and to position the presser plate in opposed relation to the first plate and squeeze the pad between the first and presser plates by a force applied to the handle carrying members.

3. In a cleaning device, a plate, a second plate fixed to and extending edgewise transversely of a face and midway the ends of the first plate and arranged with a hook portion at one end and at a side edge of the first plate, a pad of resilient absorbent material conforming to the shape of and mounted on the face of the first plate opposite the second plate, a handle member pivoted on the second plate to have transverse movement on an axis extending longitudinally of the first plate, a second handle member, a presser plate conforming in shape to the first plate pivotally mounted midway its ends on the second handle member to be disposed at the side thereof and have movement on an axis extending longitudinally of the presser plate and transversely of the second handle member, and means pivotally connected to the second handle member adapted to be engaged with the hook portion of the second plate to connect the second handle member to said second plate and permit operation of said second handle member to position the presser plate into engagement with the pad of absorbent material in opposed relation to the first plate and position the second handle member to extend adjacent and substantially parallel to the first handle member, and said handle members in said positions adapted to apply pressure to the first and presser plates.

THEODOR SEDLER.
